UNITED STATES PATENT OFFICE.

BELDEN H. BLAKE, OF CANTON, OHIO.

GOLF PAD.

Application filed June 25, 1927. Serial No. 201,448.

The invention relates to pads adapted to be worn by golf players or others engaged in games in which clubs, rackets, or the like are used.

5 It is known that there is a tendency for most golfers to overswing, carrying the head of the club back too far upon the upstroke. This is believed to be due to bending the left elbow or wrist, or permitting the fingers of 10 the left hand to at least partially release their grip upon the handle of the club. It seems that very few persons have sufficient strength in their fingers or wrists to enable them to keep the head of the club under control at 15 the top of the swing as the club head exerts its greatest force at this point, causing the wrists to bend and the fingers to release the grip on the handle.

The club head is thus out of control at the 20 time the downstroke is started and as it is next to impossible to regain the control upon the downstroke, the shot will most probably be a poor one.

It is also important that in the follow 25 through the wrists should be held just as rigid and the grip of the fingers upon the handle of the club must be just as firm. However, there is a natural tendency for the wrists to bend and the fingers to release the grip upon the handle at this point, as well as 30 at the top of the upstroke, and it is to overcome this natural tendency of the fingers to release the grip upon the handle that the present invention has been produced.

35 The object of the improvement is to provide a pad or glove having a loop or strap in the palm thereof so located that the handle of a golf club or the like when placed through this loop may be gripped in the hand in the 40 natural position and held against movement in the hand as the club is swung, preventing the natural tendency of the fingers to release the grip upon the handle at the top of the upstroke or in the follow through.

45 An embodiment of the invention is illustrated in the accompanying drawing, in which

Figure 1 is a front view of the improved golf pad;

50 Fig. 2, a perspective view of the same upon the hand;

Fig. 3, a perspective view showing the same in use, and

Fig. 4, a front view of a glove embodying the invention.

Similar numerals refer to similar parts throughout the drawing.

A right-handed golf player will wear the improved pad or glove upon the left hand and for this reason the left-hand pad and glove are illustrated in the drawing.

The improved pad 1 may be formed of leather or the like shaped as best illustrated in Fig. 1, the wrist portion terminating in the extension 2 provided with a buckle 3 and in the strap 4 provided with perforations 5, and adapted to encircle the wrist of the wearer, as illustrated in Figs. 2 and 3, to engage the buckle 3.

Straps 6 and 7 are connected to opposite sides of the upper portion of the pad 1, one of these straps being provided with a buckle 8 and the other with apertures 9 for engagement therewith.

These straps are arranged to extend around the back of the hand and to be connected by the buckle, in order to position the pad upon the hand in the manner shown in Figs. 2 and 3.

The inner side of the pad may be lined with 80 felt or the like, as shown at 10 in order to form a protection to the palm of the hand when the pad is in use.

A strap or loop 11, of leather or other suitable material, is attached to the palm of the pad. This loop is preferably adjustable as by means of the buckle 12, and is located substantially at right angles to the position of the club handle when grasped in the hand, and is so positioned that it will receive the club handle as shown in Figs. 2 and 3.

As shown in Fig. 4, the glove indicated generally at 13 may be made of any suitable material, preferably having the fingers 14 and thumb 15 cut off as illustrated to permit free use of the fingers and thumb of the player in grasping the handle of the club.

A strap or loop 16, of leather or other suitable material, is attached to the palm of the glove, similar to the loop 11, above described.

For the purpose of reinforcing the glove, as well as providing a pad to protect the palm of the hand from blisters and callouses, a piece of leather 17, substantially conforming to the palm of the glove, is stitched thereto as indicated at 18 and the straps 19 and 20,

provided with the buckle 21 and cooperating apertures 22 respectively, may be formed integral therewith for strapping around the wrist of the wearer.

5 When the club is grasped in the hand, as shown in Figs. 2 and 3, the handle of the club being located through the loop holds the club against movement in the hand, preventing the over-swinging which is a common fault 10 with golf players. It will be seen that as the club is swung upward the weight of the club is carried by this loop, thus relieving the fingers of the left hand from the strain and preventing the fingers from being partially 15 opened to release the club.

Thus the club head is brought under control before the downswing is started and the player can press as hard as he desires on the shot with no fear of dubbing it. After the 20 ball has been hit the loop again comes into play, restricting the bending of the wrists and effecting a perfect follow through.

It should further be understood that the invention is applicable to other games than 25 golf, being adaptable for use in any game where a club, bat or racket is used; and it is especially adapted for the use of tennis players, in which event, of course, the loop would be provided upon a right-hand pad or glove 30 for the use of the average right-handed per-

son, and the loop must necessarily be sufficiently large to receive the handle of a tennis racket.

I claim:

1. An article of the character described 35 including a palm portion, straps upon the palm portion arranged to be fastened around the wrist, and a loop upon said palm portion adapted to receive the handle of a club or the like. 40

2. A glove having a loop located diagonally across the palm portion thereof and adapted to receive the handle of a club or the like.

3. An article of the character described 45 including a palm portion, means for attaching the same to the palm, and an adjustable loop, adapted to receive the handle of a club or the like, said loop being so positioned on the palm portion as to restrict a swinging motion of said handle. 50

4. A glove having an adjustable loop attached to the palm portion and adapted to receive the handle of a club or the like, said loop being so positioned on the palm portion as to restrict a swinging motion of said 55 handle.

In testimony that I claim the above, I have hereunto subscribed my name.

BELDEN H. BLAKE.
